COMBINED ELECTRICAL WALL SWITCH ACTUATOR AND ESCUTCHEON PLATE

Robert E. V. Ramsing, Whittier, and Francis K. Bour-
enne, Lawndale, Calif., assignors to Sierra Electric
Corporation, Gardena, Calif., a corporation of Cali-
fornia

Filed Aug. 2, 1965, Ser. No. 86,394

Term of patent 14 years

(Cl. D26—13)

FIG. 2.

FIG. 1.

FIG. 3.

FIG. 4.

FIG. 5.

FIG. 1 is a front elevational view of a combined electrical wall switch actuator and escutcheon plate showing our new design;

FIG. 2 is a right-side elevational view thereof;

FIG. 3 is a top plan view thereof;

FIG. 4 is a bottom plan view thereof; and

FIG. 5 is a view similar to FIG. 2 but showing the actuator switch in its alternate position.

We claim:

The ornamental design for a combined electrical wall switch actuator and escutcheon plate, substantially as shown.
